(57) **CLAIM**

The ornamental design for an aerodynamic lightweight electric vehicle as shown and described.

DESCRIPTION

FIG. 1 is a perspective view of the top and left side of the claimed design.

FIG. 2 is a front elevation view of the claimed design.

FIG. 3 is a rear elevation view of the claimed design.

FIG. 4 is a left side elevation view of the claimed design.

FIG. 5 is a right side elevation view of the claimed design.

FIG. 6 is a top plan view of the claimed design.

FIG. 7 is a bottom view of the claimed design; and,

FIG. 8 is a perspective view of the top and left side of the claimed design with rear seat cover removed.

The broken lines in FIG. 8 are provided to indicate the path of projection from which the rear seat cover is removed from. These broken lines do not form part of the claimed design.
